M. A. LEY.

LITTER CARRIER.

APPLICATION FILED JUNE 27, 1912.

1,052,672.

Patented Feb. 11, 1913.

UNITED STATES PATENT OFFICE.

MICHAEL A. LEY, OF CADILLAC, MICHIGAN.

LITTER-CARRIER.

1,052,672.

Specification of Letters Patent. Patented Feb. 11, 1913.

Application filed June 27, 1912. Serial No. 706,272.

To all whom it may concern:

Be it known that I, MICHAEL A. LEY, a citizen of the United States, residing at Cadillac, in the county of Wexford, State of Michigan, have invented certain new and useful Improvements in Litter-Carriers; and I do hereby declare the following to be a full, clear, and exact description of the invention, such as will enable others skilled in the art to which it appertains to make and use the same.

The present invention is directed to improvements in litter carriers and particularly to one adapted to travel upon an overhead cable or track.

The invention has for its object to provide a carrier of this type wherein the trip operating wires may be adjusted so that the trips will be positively actuated when desired.

With these and other objects in view, this invention resides in the novel features of construction, formations, combinations and arrangements of parts to be hereinafter more fully described, claimed and illustrated in the accompanying drawing, in which:—

Figure 1 is a side elevation of the device. Fig. 2 is an end elevation of the device, partly in section. Fig. 3 is a detail perspective view of the adjusting device. Fig. 4 is a sectional view on line 3—3 of Fig. 1.

Referring to the accompanying drawing, the numeral 1 designates a cable, which may be suspended in any suitable manner. Adapted for travel upon the cable 1 is a carriage 2, depending from which is a hanger 3 to the lower end of which is secured the tubular bail 4. The ends of the bail 4 are pivotally connected to the ends of the carrier 5. Mounted upon each end of the carrier 5 is a segmental rack 6, which is adapted to be engaged by weighted pins 7, which are slidably mounted in the lower ends of the tubular bail 4. Secured to the upper end of each pin 7 is the lower end of a cord 8, said cord being operable in the bail and passed through a slot 9 formed therein. Each cord is secured at its upper end in the eye 10 carried by the threaded bolt 11, said bolt being passed through a perforation 12 formed in the right angle extension 13 of the plate 14, said plate having its upper ends terminating in a hook 15 which is adapted to engage the fork 16 formed integral with the trigger 17 which is pivotally connected to the hanger 3. An adjusting nut 18 is mounted upon the bolt 11, and is adapted to

bear against the upper face of the extension 13, said nut being operable to vertically adjust the said bolt so that the tension of the cord 8 may be regulated.

It is a well known fact that in devices of this character the trip cord for operating the weighted pins oftentimes becomes loose, thus preventing the same from being withdrawn from engagement with the racks carried by the carriers, and it is to this end that the invention is directed, and by this construction it will be readily seen that should this cord become slack it will only be necessary to manipulate the nut whereupon the bolt may be adjusted to tighten the same.

After the carrier 5 has reached the place where it is desired to dump the contents thereof it is only necessary that the cords 19 be grasped and pulled, thereby rocking the trigger 17 which draws upon the cords 8, thus removing the weighted pins from engagement with the racks 6, thus permitting the carrier to tilt.

What is claimed is:—

1. In a device of the class described comprising a carrier adapted for travel upon an elevated cable, a hanger depending from the carriage, a bail secured to the hanger, said bail being adapted to support a carrier, a trigger pivotally connected to the hanger, trip cords passable through the bail, a plate having hooks carried by its upper end and engaging the trigger, a right angle extension formed upon the lower end of the plate, a bolt passable therethrough and to the lower end of which is secured the ends of the cords, a nut engaging said bolt and operable to adjust the bolt to regulate the tension of the cords and means for rocking the trigger to operate the trip cords, to permit tilting of the carrier.

2. In a device of the class described, the combination with a supporting cable, of a carriage adapted for travel thereon, a hanger depending from the carriage, a trigger pivotally mounted on the hanger and having its lower end forked, a tubular bail secured to the lower end of the hanger and having its ends pivotally connected to a carrier, segmental racks carried by the ends of the carrier and adapted to be engaged by weighted pins slidably mounted in the lower ends of the bail, trip cords passable through the bail and having their lower ends secured to the upper ends of the weighted pins, plates having their upper ends formed with hooks

and adapted to engage with the forked ends of the trigger, the lower ends of said plates being provided with right angle extensions, perforations formed in the extensions, bolts 5 passable through the perforations and having eyes formed at their lower ends, said cords having their upper ends secured in the eyes, nuts mounted on the bolts and operable to adjust said bolts to regulate the tension of said cords and means for rocking the

trigger to shift the trip cords, whereby said weighted pins are disengaged from the racks to permit tilting of the carrier.

In testimony whereof, I affix my signature, in presence of two witnesses.

MICHAEL A. LEY.
